N. STATHAM,
ELECTROLYTIC CAUSTIC SODA CELL,
APPLICATION FILED MAY 31, 1917. RENEWED JUNE 30, 1921.
1,411,530. Patented Apr. 4, 1922.

UNITED STATES PATENT OFFICE.

NOEL STATHAM, OF HASTINGS ON HUDSON, NEW YORK, ASSIGNOR TO INDUSTRIAL CHEMICAL COMPANY, OF NEW YORK, N. Y., A CORPORATION OF NEW YORK.

ELECTROLYTIC CAUSTIC-SODA CELL.

1,411,530.

Specification of Letters Patent.

Patented Apr. 4, 1922.

Application filed May 31, 1917, Serial No. 171,835. Renewed June 30, 1921. Serial No. 481,708.

To all whom it may concern:

Be it known that I, NOEL STATHAM, a subject of the King of Great Britain, and resident of Hastings on Hudson, county of 5 Westchester, and State of New York, have made a certain new and useful invention Relating to Electrolytic Caustic-Soda Cells, of which the following is a specification, taken in connection with the accompanying 10 drawing, which form part of the same.

This invention relates especially to cathode diaphragm electrolytic cells particularly adapted for use in producing caustic alkali, such as caustic soda, from salt, the cathode 15 diaphragms being preferably constructed of special permeable material, so that the seepage of electrolyte therethrough occurs at such rate as to substantially overcome the back diffusion of the caustic soda through 20 the small passages or interstices in the diaphragm. If desired also the diaphragm may in some cases have its permeability regulated preferably by forming adjacent the discharge side of the diaphragm a relatively 25 impermeable layer of finer particles of asbestos or other material, which may be incorporated with the asbestos fibre or other material of which the body of the diaphragm may be formed.

30 In the accompanying drawing showing in a somewhat diagrammatic way illustrative embodiments of this invention,

Fig. 1 is a longitudinal section through a cell, parts being removed for greater 35 clearness.

Fig. 2 is a transverse section thereof.

Fig. 3 is an enlarged horizontal section through one of the anode elements; and

40 Figs. 4 and 5 are diagrammatic sectional views of the cathode diaphragms which may be used.

The cell body 1 may with advantage be formed of concrete and provided with a suitable impervious lining 2 of vitreous tile, 45 for instance. The concrete body may be strengthened and reenforced in suitable ways, preferably by the use of stay rods or other strengthening devices arranged outside the cell, these rods 31 being bolted or 50 otherwise connected, for instance, to the stay connectors 44 at the corners of the cell body so as to hold the parts together and strengthen the construction while minimizing all undesirable electrolytic action on the 55 stay rods and parts. As indicated in Figs. 1 and 2 suitable clamping plates, such as

42, may be cast or embedded in the cell body so as to support the cathode elements in connection therewith and these clamping plates may be secured in position by suitable clamping bolts 11 which preferably pass through insulating protecting tubes 41 of hard rubber or the like to similarly protect these bolts against electrolytic action. The cathode elements which may be clamped upon both 60 sides of the cell body to cover the open rectangular sides thereof as by the clamping dogs 32 may comprise the channel iron frames 45 in which the concrete or other cathode backing 47 may be cast or otherwise 65 formed, suitable bearing bars, such as 23, being preferably cast into this backing so as to be substantially in line with the inner edges of the frames. The cathodes in the form of perforated plates 24 of steel or 70 other suitable material may rest against these bearing bars and in turn support the cathode diaphragm 25 of suitable porous material, such as sheets of asbestos paper, preferably allowing substantially uniform 75 seepage at the different levels in contact with the electrolyte within the cell, although this is not necessary in all cases. As is usual in the Hargreaves type of cell the cathode liquor entering the cathode chamber 33 by 80 percolation or electrolytic action may run down into the caustic drip space 46 from which it may be continuously drained by the 85 usual drain pipes or passages not shown.

The anode elements within the cell may 90 with advantage comprise the anode posts 16 having bodies of graphite or other suitable material extending up through anode apertures 4 at the top of the cell body and preferably permanently built into the cell 95 body as by having the concrete or other calking 43 around their upper portions while their lower portions may be embedded in the cell lining or otherwise cast into or permanently secured to the cell body. It is advantageous to protect these anode posts against 100 disintegration or other wasting influences in the cell and for this purpose they may be first coated with a protecting insulating covering as shown in Fig. 3, in which the 105 graphite anode post bodies 20 are shown as enclosed in a covering 16 of suitable insulating material, such, for instance, as hard rubber, which may be vulcanized in place on the posts before they are assembled. The 110 thickness of this protective covering is of course considerably exaggerated in the

drawing since this coating need only be an eighth of an inch thick or less to give the desired permanence and elastic insulating properties. The anode plates are preferably 5 removably mounted on these posts by suitable connecting devices, such, for instance, as the double tapered connecting pins 19 of graphite or similar material which may fit tightly into a tapered hole in the anode posts 10 and also into similarly tapered holes in the anode plates 17, 18, which are thus mounted on each side of the post so as to properly cooperate with the cathode diaphragms. It is, of course, understood that a suitable connector 15 may be cast upon or otherwise electrically connected to each anode post adjacent its top to conduct the current thereto and similar negative connections may be made with the cathode frames or 20 plates, as is well known in this art.

As indicated in Fig. 1, the cell may with advantage be formed with a draw-off outlet, such as 6, arranged in the bottom of the cell body so as to be opened from time to 25 time so as to completely withdraw the electrolyte from the cell, this outlet being, of course, normally closed by a suitable plug or other device. A brine inlet feed pipe 21 may be cast into the cell body so as to 30 discharge brine through its inclined lower end 22, a transverse connection, such as 34, being preferably provided at about the liquid level of the cell, which may be normally closed by a removable plug or covering allowing 35 observation of the level of the electrolyte from time to time. Another testing tube or opening 40 may be arranged in the top of the cell body, this tube preferably extending somewhat below the normal electrolyte 40 level and allowing test portions to be removed therefrom or the specific gravity otherwise determined when desired. A combined chlorine and drip outlet is preferably arranged adjacent one end of the cell, the 45 outlet pipe 10 preferably having a curved portion 7 in which a normally covered clean-out hole 8 may be arranged adjacent the bend so as to allow both sections of the pipe to be cleared by suitable devices, the receiving 50 end 14 of this chlorine discharge pipe preferably communicating with the interior of the cell somewhat above the liquid level therein, which may be at about the point indicated by the dotted line in Fig. 1. A 55 brine drip discharge pipe, such as 12, may have a depending receiving end 13 within the cell and below the normal liquid level therein, the discharge end of this pipe 12 outside the cell being preferably arranged 60 to drip into the trapped drip receiver 9 so that the amount of this brine drip which is discharged from the cell may be observed from time to time as it passes into the trapped connection with the chlorine discharge pipe and thus seals this connection 65

against discharge of chlorine or entering air.

In using this type of cell for the production of caustic soda by the electrolysis of common salt, for instance, cathode diaphragms of a specially permeable character 70 are used, so that considerable percolation of brine can take place through the diaphragms even when the current is not passing. For this purpose the diaphragms may be formed of asbestos board or paper of a permeable 75 character, the asbestos fibre being formed into sheets of paper or cardboard of the desired thickness, which of course provides numerous small diameter channels or capillary passages through the diaphragm 80 through which the electrolyte tends to flow under the static pressure in the anode chamber. If desired, the amount of percolation occurring throughout the different parts of the diaphragm may be controlled by the use 85 of more or less relatively impervious or finer grained material incorporated in or applied to the diaphragm preferably adjacent its discharge side. As shown in Fig. 4, the cathode diaphragm 26, the thickness of 90 which is greatly exaggerated for the sake of clearness, may have incorporated therewith a layer 27 of less permeable material, this layer varying in thickness more or less between the upper and lower parts of the 95 diaphragm, so that at the bottom a greater thickness of this finer grain material is used which correspondingly cuts down the seepage of electrolyte and in this way a substantially uniform amount of seepage may 100 take place throughout the entire diaphragm area. Another arrangement of diaphragm is shown in Fig. 5 in which the thickness of the diaphragm is also greatly exaggerated. The diaphragm, mainly composed of 105 substantially uniform sized particles of asbestos fibre felted or laid together by paper making methods may have a number of stepped or varying thickness portions of finer grained or less permeable material 110 29, 30 arranged preferably adjacent its discharge side so that the seepage of electrolyte is thereby limited and rendered more or less uniform throughout the diaphragm area. For these purposes particles of much 115 finer grained asbestos fibre may be used and this material may be incorporated in any desired way with the fibrous material forming the body of the diaphragm, which is preferably composed of substantially uniform sized fibrous particles, during its manufacture, or if desired a coating of this or other relatively impervious material may be applied to the partly or completely formed diaphragm which is then preferably 120 compacted so as to make a substantially uniform thickness layer or sheet which cooperates to best advantage with the diaphragm mounting used. It is advantageous to have 125 these relatively impervious seepage regulat- 130

ing portions of the diaphragm at or adjacent its discharge side, since in this way solid particles or impurities carried into the diaphragm by the electrolyte in which they 5 are suspended are usually stopped and embedded in the more porous open portions of the diaphragm where they exert comparatively little influence in cutting down its permeability.

10 In the use of a cell of this character for the production of caustic soda from ordinary salt brine the seepage of brine through the diaphragm passages should preferably occur at such rate that undesirable diffusion 15 of the caustic soda formed adjacent the cathode cannot take place back through the diaphragm into the anode chamber. Caustic soda because of its much greater solubility has a much greater tendency to become dissolved in and diffused back through the electrolyte in the diaphragm than sodium carbonate would, for instance, and to prevent this undesirable action it seems necessary to have sufficient seepage or percolation of the 20 electrolyte through the diaphragm so that the velocity at which the electrolyte passes through the small interstices or capillary passages in the diaphragm is greater than the velocity of back diffusion of the formed 25 caustic soda electrolytically produced at the surface of the cathode. The use of this cell has indicated that good results are secured when the cathode liquor seeping down through the cathode chamber 33 and into the 30 drip space 46 at the bottom thereof contains about as much salt in solution as it contains of caustic. The cell is working at good efficiency when there is about 110 grams per litre of caustic soda in the cathode liquor to 35 100 to 110 grams of dissolved salt therein. The salt brine fed to the cell is preferably a fairly concentrated solution of about 40 degrees Twaddell and it is supplied to the cell in such quantities as to give a slight brine 40 discharge at the sight drip provided on the cell giving a brine discharge of about $\frac{1}{10}$ th of a litre per hour per square foot of diaphragm surface, although of course somewhat greater brine discharge may occur 45 without undesirable results. Under these conditions the cell runs efficiently without undesirable amounts of wasteful chlorate decomposition in the anode chamber and for weeks at a time cells of this character have 50 operated commercially with a current efficiency between 90 and 94 per cent of the theoretical current required for producing the caustic soda recovered.

This invention has been described in connection with a number of illustrative embodiments, forms, proportions, shapes, parts, materials, arrangements and methods of operation and use, to the details of which disclosure the invention is not of course to 55 be limited, since what is claimed as new and

what is desired to be secured by Letters Patent is set forth in the appended claims.

I claim—

1. In electrolytic cells adapted for the electrolysis of salt, an open sided cell body 70 formed of concrete and having an insulating vitreous lining, anodes mounted in said cell body and comprising anode posts provided with a hard rubber insulating protecting covering permanently embedded in the 75 lining of the cell body and projecting through anode apertures in the top of the same, renewable anode plates cooperating with said posts and double tapered connector pins connecting said plates and posts, removable cathode frames secured to said cell body to cover the open sides thereof, perforated cathode plates and permeable cathode diaphragms in contact therewith clamped between said cell body and said 80 cathode frames, said diaphragms being of varying permeability at different heights to make the seepage of electrolyte therethrough substantially uniform throughout different parts of the diaphragms. 90

2. In electrolytic cells adapted for the electrolysis of salt, an open sided cell body formed of concrete and having an insulating lining, anodes mounted in said cell body and comprising anode posts provided with a 95 hard rubber insulating protecting covering permanently embedded in the bottom of the cell body and projecting through anode apertures in the top of the same, renewable anode plates cooperating with said posts, removable cathode frames secured to said cell body to cover the open sides thereof, perforated cathode plates and permeable cathode diaphragms in contact therewith clamped between said cell body and said cathode frames. 100

3. In electrolytic cells adapted for the electrolysis of salt, an open sided cell body, anodes mounted in said cell body and comprising anode posts provided with an insulating protecting covering permanently embedded in the bottom of the cell body and projecting through anode apertures in the top of the same, renewable anode plates cooperating with said posts, removable cathode frames secured to said cell body to 110 cover the open sides thereof, perforated cathode plates and permeable cathode diaphragms in contact therewith clamped between said cell body and said cathode frames. 115

4. In electrolytic cells adapted for the 120 electrolysis of salt, an open sided rectangular sectioned cell body formed of concrete, anodes mounted in said cell body, metallic strengthening members cooperating with said cell body and arranged outside of the 125 same, clamping plates embedded in the said cell body and secured thereto by removing clamping bolts passing through said cell body and insulated therefrom by protecting tubes, removable cathode frames and clamp- 130

- ing dogs secured to said clamping plates to clamp said cathode frames to said cell body to cover the open sides thereof and having bearing bars substantially flush with the 5 inner faces of said frames, perforated cathode plates and permeable cathode diaphragms in contact therewith clamped between said cell body and said cathode frames, said diaphragms allowing seepage of electrolyte 10 therethrough at such rate as to substantially prevent back diffusion of the formed caustic soda through said diaphragms.
5. In electrolytic cells adapted for the electrolysis of salt, an open sided rectangular sectioned cell body formed of concrete, anodes mounted in said cell body, metallic strengthening members cooperating with said cell body and arranged outside of the same, clamping plates embedded in the said cell 15 body and secured thereto by clamping bolts passing through said cell body and insulated therefrom, removable cathode frames and clamping dogs secured to said clamping plates to clamp said cathode frames to said 20 cell body to cover the open sides thereof, perforated cathode plates and permeable cathode diaphragms in contact therewith clamped between said cell body and said 25 cathode frames.
6. In electrolytic cells adapted for the electrolysis of salt comprising a cell formed of concrete, anodes mounted in said cell and comprising carbon anode posts provided with an elastic insulating protecting covering permanently secured in the cell body and projecting through anode apertures in the same, renewable graphitic carbon anode plates cooperating with said posts and double tapered carbon connector pins connecting said plates and posts.
7. In electrolytic cells adapted for the electrolysis of salt, comprising a cell, anodes mounted in said cell and comprising carbon anode posts provided with an insulating 45 protecting covering permanently secured in the cell body, renewable graphitic carbon anode plates cooperating with said posts and tapered carbon connector pins connecting said plates and posts.
8. In electrolytic cells adapted for the electrolysis of salt, comprising a cell, anodes mounted in said cell and comprising carbon anode posts provided with a protecting covering, renewable carbon anode plates cooperating with said posts and renewable wedging carbon connecting portions electrically connecting said posts and plates.
9. In electrolytic cells adapted for the electrolysis of salt, comprising a cell, anodes 60 mounted in said cell and comprising carbon anode posts provided with a protecting covering and renewable carbon anode plates cooperating with said posts and tapered carbon connector pins connecting said plates 65 and posts.
10. In electrolytic cells adapted for producing caustic soda by the electrolysis of salt, a cell body, anodes mounted in said cell body, removable cathode frames secured to said cell body to cover the open sides thereof, perforated cathode plates and permeable cathode diaphragms in contact therewith clamped between said cell body and said cathode frames, said diaphragms being of substantially uniform thickness and comprising a variable thickness layer of relatively impervious material on their discharge sides to give said diaphragms varying permeability at different heights to make the seepage of electrolyte therethrough substantially uniform throughout different parts of the diaphragms, said diaphragms allowing seepage of electrolyte therethrough at such rate as to substantially prevent back diffusion of the formed caustic soda through said diaphragms.
11. In electrolytic cells adapted for producing caustic soda by the electrolysis of salt, a cell body, anodes mounted in said cell body, removable cathode frames secured to said cell body to cover the open sides thereof, perforated cathode plates and permeable cathode diaphragms in contact therewith clamped between said cell body and said cathode frames, said diaphragms being of substantially uniform thickness and comprising a variable thickness layer to give said diaphragms varying permeability at different heights, said diaphragms allowing seepage of electrolyte therethrough at such rate as to substantially prevent back diffusion of the formed caustic soda through said diaphragms.
12. In electrolytic cells adapted for producing caustic soda by the electrolysis of salt, permeable cathode diaphragms of substantially uniform thickness and comprising a variable thickness layer of relatively impervious material to give said diaphragms varying permeability at different heights, said diaphragms allowing seepage of electrolyte therethrough at such rate as to substantially prevent back diffusion of the formed caustic soda through said diaphragms.
13. In electrolytic cells, permeable cathode diaphragms comprising a variable thickness layer of relatively impervious material to give said diaphragms varying permeability at different heights.
14. In electrolytic cells, permeable cathode diaphragms comprising a variable thickness layer of relatively impervious material on their discharge sides to give said diaphragms varying permeability at different heights.

NOEL STATHAM.
